CLAIM

The ornamental design for a light therapy vest as shown and described.

DESCRIPTION

FIG. 1 is a front perspective view of a light therapy vest showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the light therapy vest in an open position; and,

FIG. 9 is a front perspective view of the light therapy vest in the open position and a flap in an open configuration.

The portions of the drawings shown in broken lines represent stitching, which does form part of the claimed design.
